DESIGN FOR A TRAILER COUPLER FITTING

John L. Gilmore, Kansas City, Mo.

Application July 24, 1939, Serial No. 86,220

Term of patent 14 years

To all whom it may concern:

Be it known that I, John L. Gilmore, a citizen of the United States and a resident of Kansas City, in the county of Jackson and State of Missouri, have invented a new, original, and ornamental Design for a Trailer Coupler Fitting, of which the following is a specification, reference being had to the accompanying drawing, forming a part thereof.

Figure 1 is a perspective view of my trailer coupler fitting.

Figure 2 is a top or plan view.

Figure 3 is a side elevational view thereof.

Figure 4 is an end elevation.

I claim:

The ornamental design for a trailer coupler fitting, substantially as shown.

JOHN L. GILMORE.
